UNITED STATES PATENT OFFICE.

WALTER J. BRUEHL, OF BUFFALO, NEW YORK.

SIGNAL DEVICE FOR AUTOMOBILES.

1,369,006.

Specification of Letters Patent. Patented Feb. 22, 1921.

Application filed May 24, 1920. Serial No. 383,774.

To all whom it may concern:

Be it known that I, WALTER J. BRUEHL, a citizen of the United States, residing at Buffalo, in the county of Erie and State of New York, have invented a new and useful Improvement in Signal Devices for Automobiles, of which the following is a specification.

This invention relates to semaphores or signal devices for use on automobiles for the purpose of indicating a change in the course or motion of the vehicle and the direction in which it is about to turn.

One object of the invention is to provide a signaling device of this nature which will not detract from the neat appearance of the vehicle on which it is used, and which is of exceedingly simple and inexpensive construction, such that the device can be readily mounted in proper position on the vehicle by an unskilled person by means of ordinary tools.

Other objects of the invention are to construct the device of a minimum number of parts arranged so that the device will not be bulky or cumbersome or complicated, and so that the semaphore arm and its operating handle or member will be normally out of the way close to the door or wall of the vehicle on which the device is mounted, and not form objectionable or unsightly projections; also to improve signal devices of the character stated in the respects hereinafter described and set forth in the claims.

35 In the accompanying drawings:—

Figure 1 is a fragmentary side elevation of an automobile provided with a signal device embodying the invention.

Fig. 2 is an enlarged sectional elevation thereof on line 2—2, Fig. 1, showing the semaphore arm in its extended position.

Fig. 3 is a sectional plan view thereof on a still larger scale on line 3—3, Fig. 1.

Fig. 4 is a detail sectional elevation showing the catch for releasably holding the semaphore arm in its different positions.

Fig. 5 is a detail sectional elevation showing the guide for the operating rod or member.

50 The signal device comprises a semaphore arm pivotally mounted on a bracket or support which is adapted to be secured on the door, side of the body or other suitable part of the vehicle, and an operating rod or member which is connected to the semaphore arm and is movable lengthwise in a guide

or hole in the door or part of the vehicle on which the device is mounted for swinging the arm to and from a position in which it projects outwardly from the vehicle, or 60 can be readily seen and gives the intended signal.

The semaphore arm 10 may be made of a thin piece of wood or of other suitable material and may be of any suitable shape. 65 This arm is suitably pivoted on a bracket or support 11 which is preferably secured on the door or side wall of the vehicle so that the arm normally extends close beside the door or wall and can swing to a position 70 in which it extends outwardly from the door or wall, but the semaphore could be differently placed on the vehicle so long as the arm can swing to a position suitable for signaling purposes. The bracket or support 11 shown is made of sheet metal and comprises a base plate 12 adapted to bear against the outer face of the door or wall of the vehicle, and upper and lower horizontal plates 13 which project outwardly 80 from the base plate and between which the semaphore arm 10 is pivoted by a pin or bolt 14 extending through the arm and through the plates 13. The bracket also preferably has an end plate or part 15 which joins the front edges of the horizontal plates 13 and together therewith forms a partial housing or inclosure for the hinged end of the semaphore arm. This bracket or support is preferably secured on the door or 90 wall 16 of the vehicle by screws or other suitable fastenings 17 passing through holes provided therefor in the base plate 13 of the bracket or support.

18 represents the operating rod which, in 95 the construction shown, is pivoted at its outer end to the semaphore arm 10 adjacent to the pivot for the latter and passes through a guide hole 19 in the base plate of the bracket 11 and through a hole 20 extending 100 through the door or wall of the vehicle in register with said hole 19 in the bracket. This operating rod is provided at its inner end, inside of the vehicle, with a handle suitable for pushing and pulling the rod to 105 swing the semaphore arm. Preferably the operating rod is provided with a hinged, inner section or portion 21 so that when the rod has been pulled inwardly to retract the semaphore to its normal position the hinged 110 inner portion of the rod can be folded to a position in which it lies close to the inner

side of the door or wall where it will be out of the way and will not form an objectionable projection within the vehicle. The hinge joint 22 for the folding section of the 5 operating rod is preferably of a construction adapted to releasably hold the hinged section stationary in either its extended or folded position and prevent accidental swinging of the handle when actuating the 10 semaphore arm.

Preferably a guide sleeve for the operating rod 18 is provided. In the construction shown this sleeve consists of two sections 23 and 24, which are inserted respectively 15 through the hole 19 in the base plate of the bracket and through the inner end of the hole 20 in the door or wall of the vehicle, the inner ends of the two sleeve sections being adapted to fit tightly one within the 20 other, or to be connected together in any other suitable manner to retain the parts of the guide sleeve in place. The guide sleeve has flaring ends or is otherwise suitably shaped so as to guide the operating rod 25 and permit the angular movement of the rod incident to the connection of the rod with the swinging arm 10. This guide sleeve not only furnishes a guide in which the operating rod is adapted to slide and swing freely 30 to the necessary extent, but in addition, it provides a neat cover or finish for the holes in the base plate of the bracket 11 and in the door or wall of the vehicle.

In order to releasably retain the 35 semaphore arm stationary in either its retracted or projecting position and relieve the driver of the vehicle from the necessity of holding the semaphore in its extended position, and also prevent looseness and rattling of 40 the parts, the arm is preferably provided with a suitable catch adapted to engage the bracket 11 to hold the arm in its two positions. The catch shown for this purpose consists of a spring pressed ball 25 mounted 45 in the inner end of the semaphore arm and adapted to spring into either of two depressions or notches 26 and 27 in the adjacent portion of the bracket 11. When the semaphore arm is in its inner or inoperative position the ball will seat in the depression 26 and releasably hold the semaphore stationary in this position and when the semaphore is swung to its projecting position the ball will seat in the other depression 27 55 and releasably hold the semaphore in this position. While this catch retains the semaphore stationary in the two different positions, the application of a slight force will release the catch and permit the movement 60 of the semaphore. The ball is confined within a cylindrical case 28, Fig. 4, which is retained in a hole in the semaphore arm 10 and the ball is pressed outwardly against the opposing portion of the bracket by a

spring 29 confined in the case beneath the 65 ball.

To apply the device to a vehicle, it is only necessary to place the device against the door or wall of the vehicle in the desired position and mark on the door or wall the 70 positions of the holes in the base plate 12 for the operating rod and for the fastening screws for the bracket. The hole 20 is then bored through the door or wall for the passage of the operating rod 18 and the bracket 75 is secured on the door with the hole 19 in the base plate 12 in register with this hole in the door or wall. The bracket is then secured in place by means of its screws or fastening devices and the guide sleeve 80 23-24 for the operating rod is secured in the holes in the bracket and door. Since the base plate of the bracket to which the semaphore is hinged is provided with a hole 19 therein for the passage of the operating rod, 85 this hole definitely defines the position in which the hole must be made in the door or wall of the vehicle and it is practically impossible for a person, even though unskilled, to improperly place the device on the vehicle or spoil the vehicle by making the 90 hole for the operating rod at the improper place.

I claim as my invention:

1. The combination of a semaphore arm, 95 a support to which the arm is pivoted and which is adapted to be secured on a wall or part of a vehicle, and an operating rod connected to said semaphore arm and extending therefrom through a hole in said wall or 100 part of the vehicle and adapted to be moved lengthwise in said hole for swinging said arm in and out toward and from the vehicle, a guide sleeve surrounding said operating rod in said hole in the wall or part 105 of the vehicle, and comprising detachably connected sections extending into said hole from the inner and outer ends thereof and being detachably connected at their inner ends.

2. The combination of a semaphore arm, 110 a support comprising a base plate adapted to be secured on a part of a vehicle, spaced horizontal plates projecting from said base plate and between which said arm is pivoted, and an end plate joining the front edges of said horizontal plates whereby said support provides a housing partially inclosing the pivoted end of the arm, and an operating rod connected to said semaphore 115 arm and extending through a guide hole in said base plate, said semaphore arm being swung toward and from the vehicle by the movement of said operating rod lengthwise 120 through said guide hole.

3. The combination of a semaphore arm, 125 a supporting member adapted to be secured to a wall or part of an automobile and to

which said arm is pivoted, whereby said arm may be swung in and out toward and from the vehicle, a latching member on the inner end of said arm, and latching members on 5 said support for coöperating with the latching member on said arm whereby the arm may be releasably held in its inner and projecting positions, and an operating rod con-

nected to said arm whereby said arm may be swung. 10

Witness my hand this 24th day of April, 1920.

WALTER J. BRUEHL.
